Patented Aug. 6, 1968

211,872

CHECK VALVE

Loyd L. Reynolds, 21 W. Reno,
Oklahoma City, Okla. 73102

Filed Dec. 14, 1967, Ser. No. 9,775

Term of patent 14 years

(Cl. D23—22)

FIG. 4

FIG. 1

FIG. 3

FIG. 5

FIG. 2

FIG. 6

FIGURE 1 is a side elevational view of a check valve showing my new design.

FIGURE 2 is an elevational view of the opposite side of FIGURE 1.

FIGURE 3 is a right end view of FIGURE 1.

FIGURE 4 is a top view of FIGURE 1.

FIGURE 5 is a left end view of FIGURE 1; and,

FIGURE 6 is a bottom view of FIGURE 1.

The dominant features of the design reside in the portions shown in full lines.

I claim:

The ornamental design for a check valve, substantially as shown and described.
